UNITED STATES PATENT OFFICE

MILLARD CATRON, OF CINCINNATI, OHIO

WINDOW LOCK

Application filed October 30, 1929. Serial No. 403,539.

This invention relates to new and useful improvements in window locks to maintain same in locked position while the sashes are partially separated to facilitate ventilating of a room without subjecting same accessible to unauthorized entry.

Another object of the invention comprehends the provision and arrangement of dual lock members whereby both sashes will be rigidly held in adjusted position.

A further object of the invention embodies an operating lever for controlling the dual locking members.

More specifically stated the window sashes are provided with attaching plates for connection with the locking members.

With the above and other objects in view, the invention further consists of the following novel features and details of construction, to be hereinafter more fully described, illustrated in the accompanying drawings and pointed out in the appended claims.

In the drawings:—

Figure 1 is a fragmentary elevation of the adjacent portions of the sashes for a window showing the present invention applied and in use.

Figure 2 is a horizontal sectional view taken on line 2—2 of Figure 1.

Figure 3 is a detail sectional view taken on line 3—3 of Figure 1.

Figure 4 is a sectional view taken on line 4—4 of Figure 2.

Referring to the drawings in detail wherein like characters of reference denote corresponding parts, the reference character 10 indicates generally a window frame having upper and lower sashes 11 and 12 respectively slidably mounted upon the opposite sides of a parting strip 13. The innermost or lower sash is held against the parting strip by stops 14. The latter will be again alluded to in the following description of the invention.

In carrying out the invention, I provide a housing 14 having a tab or ear 15 laterally projecting from the bottom thereof and which is apertured to accommodate fastening elements to secure the housing upon the upper side of the upper rail of the lowermost

or inner sash in the manner shown in Figures 1, 2 and 3 of the drawings.

Gear members 16 and 17 lying flush against the upper surface of the bottom wall of the housing and intermeshed in the manner suggested in Figures 2 and 4 of the drawings are designed for simultaneous operation in different directions. Locking members, generally indicated as at 18, are provided with vertically and horizontally disposed portions 19 and 20. The vertically disposed portions of the locking members are fixed to said gears and journaled within the bottom wall of the housing. A rack bar 21 slidably mounted within an extension 22 of tubular formation carried upon one side of the housing 14 has the teeth therefor contacting with the teeth of the adjacent gear member 17 through an opening provided in the adjacent side wall of the housing.

A fulcrum or operating lever 23 pivotally mounted as at 24 upon the inner face and upper rail of the lower sash and within a pocket 25 in a form of cover plate 26 is in turn pivotally associated with the outermost 75 projecting end of the rack bar 21 through the instrumentality of a bifurcated joint.

Attaching plates 27 and 28, carried at appropriate heights upon the upper sash 11 and the sash stop 14, are provided with elongated horizontally disposed slots 29 to accommodate the extremities of the horizontally disposed ends of the locking members 18. The horizontally disposed end of the locking member, carried by and operable in conjunction with the gear member 17, is offset or otherwise distorted for an appreciable distance in order that the extremity thereof may be adequately disposed within the elongated horizontally disposed slots in the attaching plate 28. The attaching plate 28 necessarily conforms to the shape of the sash stop by having a general appearance of an angle plate, in this instance, whereas the attaching plate 27 is curved to free or skip the integral moulding upon the inner edge of the uppermost sash. Those portions of the upper sash 11 and sash stop 14 are gouged or otherwise cut away immediately behind the elongated horizontally disposed slots 29 to facilitate 100

projecting of the extremities of the horizontally disposed portions of the locking members. Incident to the arrangement and association of the gear members, rack bar and locking members, it is to be noted that in a single operation of the fulcrum lever 23, both of the locking levers are operated in different directions to lock both sashes against displacement. Through the several 10 adjustments afforded by the present invention, it is to be noted that both or either of the sashes may be elevated or otherwise separated from the adjacent portions of the window frame and locked in such positions to permit of the desired amount of ventilation. 15 The invention is susceptible of various changes in its form, proportions and minor details of construction, and the right is herein reserved to make such changes as properly fall within the scope of the appended claim. 20

Having thus described the invention, what is claimed is:

A locking mechanism for the sashes of window frames comprising a housing located 25 upon the upper side and rail of the frame lower sash, attaching plates carried upon the upper sash and the stop for the lower sash having horizontally disposed elongated slots, gear members intermeshed and disposed 30 within said housing, locking members of L-shape formation having the vertical portions thereof journaled within the housing and fixedly connected with the gear members for simultaneous operation therewith in dif- 35 ferent directions to dispose the extremities thereof within the slots of the attaching plates, an extension of tubular formation carried upon one side of the housing having an opening in communication therewith, a 40 rack bar slidably mounted within the bore of the extension and meshingly engaged with the teeth of the adjacent gear member, and an operating lever mounted upon the afore- 45 mentioned rail of the lowermost sash being operatively connected with the outermost projecting end of the rack bar.

In testimony whereof I affix my signature.
